DESIGN FOR A TEXTILE FABRIC OR SIMILAR ARTICLE

Gustav M. Pulitzer, New York, N. Y., assignor to Goldstein-Wilkins Corporation, New York,
N. Y.

Application July 14, 1933. Serial No. 48,707

Term of patent 3½ years

To all whom it may concern:

Be it known that I, GUSTAV M. PULITZER, a citizen of the United States of America, residing at 145 West 36th Street, New York, New York, have invented a new, original, and ornamental Design for a Textile Fabric or Similar Article, of which the following is a specification, reference being had to the accompanying drawing, forming a part thereof.

The figure is a plan view of a textile fabric showing my new design.

I claim:

The ornamental design for a textile fabric or similar article as shown.

In testimony whereof I have signed this specification.

GUSTAV M. PULITZER.
